(57) **CLAIM**

The ornamental design for a syringe, as shown and described.

DESCRIPTION

FIG. 1 is a perspective view of a syringe according to a first embodiment of the invention;

FIG. 2 is a side elevation view of the syringe of FIG. 1;

FIG. 3 is a front elevation view of the syringe of FIG. 1;

FIG. 4 is a rear elevation view of the syringe of FIG. 1;

FIG. 5 is a top plan view of the syringe of FIG. 1;

FIG. 6 is a bottom plan view of the syringe of FIG. 1;

FIG. 7 is a perspective view of a syringe according to a second embodiment of the invention;

FIG. 8 is a side elevation view of the syringe of FIG. 7;

FIG. 9 is a front elevation view of the syringe of FIG. 7;

FIG. 10 is a rear elevation view of the syringe of FIG. 7;

FIG. 11 is a top plan view of the syringe of FIG. 7;

FIG. 12 is a bottom plan view of the syringe of FIG. 7;

FIG. 13 is a perspective view of a syringe according to a third embodiment of the invention;

FIG. 14 is a side elevation view of the syringe of FIG. 13;

FIG. 15 is a front elevation view of the syringe of FIG. 13;

FIG. 16 is a rear elevation view of the syringe of FIG. 13;

FIG. 17 is a top plan view of the syringe of FIG. 13;

FIG. 18 is a bottom plan view of the syringe of FIG. 13;

FIG. 19 is a perspective view of a syringe according to a fourth embodiment of the invention;

FIG. 20 is a side elevation view of the syringe of FIG. 19;

FIG. 21 is a front elevation view of the syringe of FIG. 19;

FIG. 22 is a rear elevation view of the syringe of FIG. 19;

FIG. 23 is a top plan view of the syringe of FIG. 19; and,

FIG. 24 is a bottom plan view of the syringe of FIG. 19.

The opposing side elevation views for each of the four depicted embodiments are the mirror image of FIGS. 2, 8, 14, and 20 respectively.
